UNITED STATES PATENT OFFICE.

ALFRED F. MASURY, OF NEW YORK, N. Y., ASSIGNOR TO INTERNATIONAL MOTOR COMPANY, OF NEW YORK, N. Y., A CORPORATION OF DELAWARE.

SEAT.

Application filed September 27, 1926. Serial No. 137,920.

The present invention relates to swivel seats of the type adapted for use in motor busses, etc., where it is desirable to secure the seat against movement normally, but 5 where the seats may be rotated and secured to face in a plurality of directions.

An object of the present invention is to provide a swivel seat capable of being turned to a plurality of positions and to 10 devise an effective means to hold the seat against normal relative movements but to permit adjustment of the seat with ease.

Reference will now be had to the accompanying drawings for a more detailed description of the invention wherein:

Figure 1 is an elevation, in section, of one form of the invention.

Figure 2 is a plan view, partly in section, of the device of Figure 1, the section being 20 on line 2—2 of Figure 1.

Figure 3 is a detail view, partly in section, of the latch means and is taken on line 3—3 of Figure 2.

Figure 4 is a slightly modified form of 25 the invention shown in Figures 1, 2 and 3.

In the drawings *a* is a base or pedestal which is formed with a vertical cylindrical portion *a'* and a dog *a''*. The seat frame *b* has a downwardly extending shaft *b'* which 30 is received in the cylindrical portion *a'* and a spring *c* and cap *c'* serve as a thrust bearing to receive the weight of the seat and occupant.

A flange *b''* on shaft *b'* has double cam 35 surfaces *b³* and *b⁴* and between these cam portions are formed notches *b⁵* which are engaged by the dog *a''* to hold the seat against relative movement.

The spring *c* normally thrusts the seat 40 upwardly and, if the seat is turned to a mid position, causes a cam to engage the dog and turn the seat to face in either direction. The crest of each double cam portion is half way between the two notches, so 45 that, should the seat be pushed down and partially turned, upon relieving the downward pressure the force of the spring in

pushing the cam against the dog will turn the seat until the dog engages the nearest notch.

It is apparent that to reverse the position of the seat it is necessary only to push the seat down and rotate it sufficiently to engage the cam under the dog. Further turning of the seat until the dog has passed 55 over the ridge of the cam results in the dog slipping into place under the force exerted by the spring on the seat.

Figure 4 illustrates a form in which the bottom *b* of the seat frame is mounted on a 60 pedestal or shaft *b'* which rests directly on the floor. The back and arm of the seat are unitary and independent of the seat and are indicated at *d*. Formed on the bottom of this unitary structure is a sleeve *d'* which 65 fits over the shaft *b'*.

The flange and latch means is formed on this sleeve and a spring *c* serves to actuate the latching device as in the previously described construction. The advantage of this 70 form is that the arms only need be depressed to reverse the seat, and since normally but slight pressure is placed upon the arms, a relatively light spring may be used for the thrust bearing.

Other modifications may be designed 75 which fall within the scope of this invention and it is not to be limited except as defined in the appended claim.

What I claim is:

In a seat wherein the seat frame is supported in the base with capability for relative movements, a base, a seat frame mounted therein, a flange on the seat frame, a plurality of double cam faces carried by 80 the flange, notches between the cam faces, a dog carried by the base and a spring resisting downward movement of the frame to engage the dog with the notches and cam faces.

This specification signed this 23rd day of 85 September A. D. 1926.

ALFRED F. MASURY.
